Inventor:

Jacob Voegtle.

United States Patent Office.

JACOB VOEGTLE, OF INDIANAPOLIS, INDIANA.

Letters Patent No. 76,564, dated April 7, 1868.

IMPROVEMENT IN STOVE-DRUMS.

The Schedule referred to in these Letters Patent and making part of the same.

TO ALL WHOM IT MAY CONCERN:

Be it known that I, JACOB VOEGTLE, of Indianapolis, in the county of Marion, and State of Indiana, have invented a new and valuable Improvement in Heat-Regulators; and I do hereby declare that the following is a full, clear, and exact description of the construction and operation of the same, reference being had to the annexed drawings, making a part of this specification, and to the letters and figures of reference marked thereon.

The object of my invention is to construct a heat-regulator for use in drums, stove-pipes, and the like, that shall be more perfect, complete, and economical than any similar device heretofore known or used.

A plan view of my regulator is represented by Figure 1 of the drawings.

The letter F is the inner cylinder; letter E is the outer cylinder; and letters D represent a series of small cylinders that are set on the outside of both. Letter α is a damper constructed in the shape of a disk, hung at its centre, inside cylinder F, by a rod, as shown, and by which it is operated. Said rod extends, on one side, to the outside of my regulator, and has attached to it there a thumb-piece, by which it may be easily moved. Small spurs extend from said thumb-piece where it joins the regulator, by means of which the damper is held in a notch in the regulator, in any desired position.

Letter B represents a perforated ring, the apertures in which correspond in size and shape to similar openings in cylinder F. A rod extends from this ring to the outside of cylinder E, and said rod has a thumb-piece attached thereto, by which said ring is moved backward or forward, and thereby the said openings in cylinder F opened or closed at will. Letter C is a perforated plate set at right angles with the ring B, and adjusted to open or close apertures corresponding with its own, leading from the space formed above the plate G next mentioned. Plate C has also a thumb-piece, by which it is operated, outside the cylinder E. Letter G represents another perforated plate, with thumb-piece attached, and its openings correspond with apertures on the bottom of the regulator.

Near the top of my regulator, and on the outside of cylinder F, I attach another ring, marked H. It has openings into cylinder F, and it also has an arm and thumb-piece extending to the outside of the regulator, by which it is moved backward or forward, as the case may require, to open or close the openings in cylinder F, last mentioned.

The drawings properly represent my regulator as having the form of an upright tower, of the Corinthian order of architecture, of which the summit and base have the same circumference; and the small outer cylinders D have the appearance of columns set between a base and capital, which constitutes the base of the regulator. Between the plates G and C is a chamber of about ten inches in depth, more or less, and a chamber of a similar depth is left between the bottom and top of the capital.

Over the top of the capital is a movable perforated plate, rounded in the form shown on the drawings, marked K. It fits closely over said top, and its openings correspond in size and number with openings left in said top. It is operated by means of a thumb-piece, and opens or closes the chamber in the capital at the will of the operator.

My regulator is operated as follows: The cylinder F fits closely over the pipe of the stove or furnace, and the heat is first received therein. If it be desirable to allow the heat to pass from cylinder F to cylinder E, the damper α and ring C are adjusted accordingly. To allow the heat to pass into the chambers in the base and capital, I move the plates C and H, so as to open the apertures leading thereto respectively. To allow the heat to pass into the room, I open the top and bottom of the regulator by moving the plates G and K.

By means of these several devices, I am enabled to regulate the heat from a stove or furnace in such manner as to approximate to a perfect control thereof, and hence to economize in the use of the same to a far greater extent than can be accomplished by any other device for that purpose heretofore known or used.

I do not claim that either of the devices herein described is new *per se*, or that the combination of any two

of them is entirely novel. The form and shape of my regulator, however, as an ornament, have no equal, and the entire combinations described have never before been invented or known.

What I claim as my invention, and design to secure by Letters Patent, is—

A heat-regulator, having cylinders F, E, and D, damper *a*, rings B and H, and plates C, G, and K, constructed, arranged, and combined substantially as and for the purposes herein specified.

JACOB VOEGTLE.
